BRASSIÈRE

Santa Majorana, St. Albans, Long Island, N. Y.

Application September 5, 1946, Serial No. 694,901

2 Claims. (Cl. 2—42)

1

This invention relates to an improved brassière and has among its objects the provision of a brassière which will give uplifting support to the breasts of the wearer while allowing perfect freedom of motion to the arms and torso and while avoiding undesirable pressure, stresses or pinching of the flesh of the wearer, which will allow for firm anchorage of the shoulder straps without binding or cutting action while preventing the straps from slipping off the shoulders, which is constructed in such a manner as to eliminate all hooks across the back thereby creating an aesthetically pleasing, smooth, unbroken contour across the back and simultaneously eliminating any possibility of accidental unfastening, and which is further constructed in its back portion in such a manner as not to ride up the back of the wearer and not to be visible when worn under low-backed evening gowns.

I achieve the above objects by providing my brassière with a preferably bias-cut wide back portion of elastic material extending across the back of the wearer between the underarm side seams of the brassière. This elastic back portion is preferably cut to set low across the back and may further be provided with fastening means for anchorage to a girdle or similar garment.

A complete understanding of the nature of the invention and the manner in which my improved brassière attains the objects hereinabove enumerated as well as certain other objects and advantages will be readily apparent from the following description of a preferred embodiment taken in connection with the accompanying drawing, wherein:

Fig. 1 is a front view of the brassière on a wearer.

Fig. 2 is a rear view of the brassière on a wearer.

Fig. 3 is a fragmentary view of the front portion of the brassière as seen from the rear.

Fig. 4 is a fragmentary view of the elastic back portion of the brassière as seen from the front.

Fig. 5 is a fragmentary detail on an enlarged scale of part of the back portion of the brassière illustrated in Fig. 4.

Fig. 6 is a fragmentary detail on an enlarged scale and partly broken away of part of the front portion of the brassière illustrated in Fig. 3.

Fig. 7 is a sectional view taken on line 7—7 of Fig. 6; and

Fig. 8 is a sectional view taken on line 8—8 of Fig. 5 illustrating one method of securing a fastening device to the lower edge of the elastic back portion of the brassière.

Referring to the drawing my improved brassière is shown having a front portion 10 presenting a pair of breast-receiving cups 11 centrally joined at seam 12 and hemmed at its lower edge by a strip or ribbon 13. The cups 11 may be of any suitable textile material and may be shaped in any conventional manner, the illustrated embodiment, however, showing them as being formed into cup-like configurations by means of a seam 14 extending downwardly to strip 13 and presenting approximately centrally disposed apices 15 along the upper edges of each cup 11.

The cups 11 terminate laterally under the arm-pits of the wearer. The back portion 16 of the brassière is preferably of bias cut elastic material conveniently formed of two side sections 17 symmetrical about a central back seam 18 and joined to the lateral underarm edges of cups 11 by underarm side seams 19, said side sections being defined by upper edges 20 and lower edges 21. Of course, the back portion 16 may consist of a single piece of material instead of the two symmetrical side sections 17. In any event the back portion 16, starting from the underarm side seams 19, extends generally downwardly across the back of the wearer and is preferably formed with a centrally depending section 22 defined by upper edges 23 and lower edge 24 which are each on a lower level than upper edge 20 and lower edge 21 respectively of side sections 17. The upper and lower terminal edges 20 and 21 of side sections 17 and the edges 23 and 24 of the centrally depending section 22 may be, but are not necessarily, parallel. Inelastic shoulder straps 25 of satin, silk or the like are provided extending from the apices 15 of cups 11 to the back portion 16. The back portion 16 is provided with the centrally depending section 22 in order to adapt the brassière to be worn with a low-backed gown and for an additional purpose to be hereinafter indicated.

The lower edge 24 of the back portion 16 may be provided with means for anchoring said back portion to a girdle or similar garment for the purpose of maintaining uplifting support to the breasts of the wearer while simultaneously preventing the back portion from riding up the back of the wearer. This anchoring means may conveniently take the form of a plurality of hooks or the like 26 arranged at spaced intervals along the lower edge 24 of back portion 16 and which may be easily secured to a girdle or the like. As illustrated in Fig. 8 the hooks 26 may be stitched to the inside of the lower edge 24 of back portion 16.

The provision of the bias cut elastic back portion 16 results in a number of considerable advantages. The high underarm control at the underarm side seams 19 serves to keep the breasts in proper position within the cups 11 without undue pressure or distortion. There is no undesirable pressure at the point of attachment of the shoulder strap 25 to the elastic back portion 16. Firm anchorage of the shoulder strap 25 is effected while eliminating any possibility of cutting or pinching across the shoulder or slipping off the shoulder, as a result of the yieldable bias pull when the arms are raised and lowered. Perfect freedom is assured, regardless of any motion of the arms or torso.

The centrally disposed vertical seam 18 across the centrally depending section 22 of back portion 16 eliminates the use of the conventional hook fastener and creates an aesthetically pleasing, smooth, unbroken contour across the back of the wearer. This latter arrangement also eliminates the possibility of accidental unfastening.

The centrally depressed or depending section 22 adapts the back portion 16 of the brassière to be set low on the back so as not to be visible under a low-backed gown. The anchoring means 26 secured to the lower edge 24 of said depending section adapts the back portion 16 to be fastened to a girdle or similar garment for a greater degree of uplifting support to the breasts and effectively eliminates riding up the back portion 16. Even when worn unfastened to a girdle the brassière is designed and constructed to set lower across the back of the wearer than brassières of conventional design and will still give firm uplifting support to the breasts. In addition the back portion 16 will not be visible above the edge of a slip as is usually the case with conventionally designed brassières.

The bottom edges 21 and 24 of the bias-cut elastic back portion 16 do not cause any pressure or pinching of the midriff as a result of the yieldable bias pull and overcome the so-called roll around the waist, contributing toward a smooth fit and appearance. The width of the elastic back portion 16, starting from the underarm side seams 19 and extending across the back of the wearer, serves to smooth out surplus flesh, thereby further adding to comfort and general good appearance.

Another commonly observed defect in conventional brassières is a wrinkling or sagging effect in the front of the brassière below the breast cups which is largely caused by the riding up of the back portion of the brassière due to the combined effect of the weight of the breasts and the continual body movement of the wearer in walking, bending, etc. While this undesirable effect is substantially overcome in my improved brassière in a majority of cases by reason of the design and structural features previously described, it may be desired where the brassière is to be applied to a person having a full bosom to further neutralize this effect. For this purpose the cups 11 of the brassière may be provided with reinforcement sections 27 of a suitable material. As illustrated in Fig. 3, the reinforcement sec-

tions 27 have a pair of lateral edges, a bottom edge and a concave top edge 28 and may conveniently be secured to the inside of cup 11 along underarm side seam 19, bottom strip 13 and central seam 12, leaving free the concave top edge 28 to afford the necessary amount of flexibility and freedom of motion consistent with the comfort of the wearer. The reinforcement sections 27 not only serve the purpose of giving added strength to the front of the brassière and preventing sagging and wrinkling of the brassière at the bottom of the cups 11, but in addition result in greater support for the breasts and is a highly desirable feature of my improved brassière in its application to larger bosoms.

Since certain modifications may be made in the brassière of my invention without departing from the scope thereof, it is intended that all matter contained in the above description and illustrated in the accompanying drawing be interpreted merely as illustrative and not in a limiting sense.

I claim:

1. A brassière comprising a front portion having breast receiving cups extending laterally to approximately the armpits of the wearer, a back portion of bias-cut elastic material comprising two side sections arranged symmetrically about a vertical, centrally disposed seam and extending generally downwardly across the back of the wearer from the terminal underarm edges of said front portion, said side sections being shaped to define a centrally depending section extending downwardly to approximately the waist of the wearer and having a depressed upper edge, a pair of inelastic shoulder straps interconnecting each cup with said back portion and a plurality of fastening means secured to the lower edge of said depending section for anchoring said back portion to a girdle or similar garment.

2. A brassière comprising a front portion having breast receiving cups and terminating in lateral edges at approximately the armpits of the wearer, a back portion of bias-cut elastic material having a centrally depending section extending downwardly to approximately the waist of the wearer and provided with a depressed upper edge, a pair of shoulder straps interconnecting each cup with said back portion, each cup having a lower, inner reinforcement section to prevent wrinkling and sagging at the front portion of the brassière, each reinforcement section having a free concave upper edge and a plurality of fastening means secured to the lower edge of said depending section for anchoring said back portion to a girdle or similar garment.
